AMMUNITION REPAIR APPARATUS

Arthur R. Kinzle, Davenport, Iowa

Application September 21, 1945, Serial No. 617,885

3 Claims. (Cl. 86—1)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to improvements in apparatus for the repair and renovation of ammunition. More particularly the invention is concerned with the renovation and repair of artillery ammunition, specifically ammunition ranging from 20 mm. upwardly.

During combat conditions, relatively large quantities of ammunition are rendered unserviceable because of damage incurred in handling and deterioration caused by weather conditions. Other relatively large quantities of ammunition are lost. It has recently become an important phase of the operations of rear echelon units to salvage damaged ammunition and to locate to as great an extent possible ammunition theretofore considered lost and to renovate or repair such ammunition, or at least disassemble same, so that the various components thereof may be re-used. The present invention is concerned primarily with the renovation of artillery ammunition of the fixed type, in which the cartridge comprises a projectile and a shell casing crimped or otherwise fixed to the projectile. In the renovation and repair of such ammunition it is necessary to disassemble the shells so that the shell casing may be repaired or salvaged and so that the explosive in the propelling charge may be saved and used for other purposes.

Accordingly, a principal object of the present invention is to provide an apparatus useful in the disassembly of ammunition for the purpose referred to above.

It is an important object of the invention to provide an apparatus that is simple in construction and preferably portable so that it may be easily transported from one location to another.

It is likewise an important object of the invention to provide an apparatus comprising gripping or vise means for securing the projectile of the shell and to provide means by which the casing may be gripped and axially removed from the projectile.

It is another object of the invention to provide an apparatus that is adapted for use in the disassembly of various sizes of ammunition.

Other objects and important features of the invention and the use thereof will become apparent as the disclosure is more fully made in the following detailed description of a preferred embodiment of the invention as illustrated in the accompanying sheets of drawings in which:

2

Fig. 1 is a plan view of the disassembling apparatus, a shell being indicated in place in broken lines;

5 Figs. 2 and 3 are respectively side and end elevations of the structure shown in Fig. 1;

Fig. 4 is a transverse section taken on the line 4—4 of Fig. 1;

10 Fig. 5 is a plan view, on an enlarged scale, of the lower member or jaw of the vise or projectile-gripping means;

Fig. 6 is a bottom view of the upper member of the vise or projectile-gripping means;

15 Figs. 7 and 8 are respectively detail front and end views of one of the adapters used in the projectile-gripping means;

Fig. 9 is an enlarged sectional view showing the construction of the detent means for locking the projectile-gripping means in various positions of adjustment on the base; and

20 Fig. 10 is a perspective view, on an enlarged scale, of the rim-gripping element.

The apparatus chosen herein for the purposes of illustration and description is of a preferred form and it will be understood that the invention 25 may assume various other forms. Consequently, the disclosure herein should be taken as illustrative and not limiting.

The apparatus comprises a main frame or base 10 including a pair of parallel, longitudinally running side frame members 11, each of which is preferably in the form of a channel, the members being arranged with their flange portions facing inwardly and extending toward one another. The channel members 11 are rigidly cross-connected at one end by a transverse plate 12 and are further rigidly cross-connected intermediate their ends by a pair of transverse bars 13. As best shown in Fig. 4, the channel members 11 carry therebetween a pair of cradle means or shell supports, each of which is in the form of a transverse member 14 formed at its opposite sides with longitudinally running grooves 15 adapted to slidably fit the respective upper flanges of the channels, whereby the member is carried for longitudinal adjustment on the base 10. Each member 14 is formed at its center with a semicircular cutout and carries a V-block 16 for vertical adjustment by means of bolts 17 threaded into the member 14 and cooperating with slots 18 in the V-block 16.

At its rearward end the base 10 carries, for longitudinal sliding movement on the two upper flanges of the channel members 11, a transverse member or head 19 formed with a semicylindrical cutout 20 in which is recessed a semicircular

adapter 21 (Fig. 10). This adapter is formed with a semicircular groove 22 which serves to grip the rim of a shell case mounted in the V-blocks 16. Various sizes of adapters such as the one indicated at 21 may be positioned in the semicircular recess 20 in substitution for the one shown, to accommodate shell cases of different calibers and types. The transverse plate 12 at the rear end of the base 10 carries rigidly thereon an internally threaded nut 23 through which is threaded a longitudinal screw 24. The forward end of the screw 24 passes through a transverse cross member 25 rigidly secured by bolts 26 to the transverse member 19 and is secured against longitudinal movement with respect to the member 25 by means of a nut 27. An operating handwheel 28 is keyed or otherwise secured to the rear end of the screw 24 and serves as means by which the screw may be rotated in the nut 23 to move the member 19 and its associated parts longitudinally on the base 10.

A forward portion of the base carries thereon vise or gripping means for gripping the projectile of a cartridge mounted in the apparatus. This vise includes a lower jaw member 29 and an upper jaw member 30. The lower member 29 is provided at opposite sides thereof with longitudinal grooves 29a by means of which the jaw member is mounted on the two upper flanges of the channel members 11 for longitudinal movement therealong. As best shown in Fig. 9, the jaw member 29 carries at each side thereof means for cooperating with the respective channel member 11 for locking the vise in any of the various positions of longitudinal adjustment on the base 10. This means preferably comprises a bracket 31 which is secured by bolts 32 to the jaw member 29 and which includes a transverse sleeve 33 provided with a transverse bore 34. A plunger 35 is carried slidably in the bore 34 and is normally spring pressed by a compression spring 36 into engagement with any one of a plurality of transverse openings 37 provided in the channel member 11 adjacent the upper edge thereof. The outer end of the plunger 35 is threaded as at 38 into the radially flanged portion of an operating member 39. This member is in the form of a hollow cylinder, encircling the sleeve 33 and slideable thereon, and serving as means by which the operator may retract the plunger 35 from an opening 37 against pressure of the spring 36. It will be understood that the detent means at the opposite side of the base is the same as that just described.

The lower jaw member 29 is provided at one side thereof with an upstanding longitudinally apertured ear 40 which, by means of a pin 41, pivotally carries one end of the upper jaw member 30, the end of the latter being provided with a pair of apertured ears 42 for that purpose. The upper member 30 is formed as an arc complementing the arc of the lower jaw member 29 and is formed at its opposite side with a bifurcated portion providing a pair of ears 43. The lower jaw member is provided at this side with a pair of ears 44 through which is passed a pin 45 that carries an upstanding eyebolt 46. The shank of the eyebolt 46 is threaded into a vertical threaded sleeve 47 having at its upper end an operating handle 48. When the threaded sleeve 47 is loosened sufficiently, it and the eyebolt 46 may be swung outwardly about the axis of the pin 45 and free of the ears 43 so that the upper jaw member 30 may be swung upwardly about its pivot pin 41.

As best shown in Fig. 5, the lower jaw member 29 is slotted transversely at the base as at 49 and the opposite transverse portions forming the slot 49 are formed respectively with vertical recesses or pockets 50. As shown in Fig. 6, the upper member 30 is provided with a transverse slot 51 similar to the slot 49 in the member 29. The member 30 is likewise provided with a pair of opposed pockets or recesses 52 similar to the recesses 50 in the member 29. In addition, the upper member 30 is provided with a pair of coaxial bores 53 extending through the member 30 and into the recesses 52.

The lower and upper jaw members 29 and 30 are adapted respectively to carry adapter jaws 54 and 55. Each adapter jaw is formed as shown in Figs. 7 and 8 and includes a central portion provided with a plurality of shell-engaging notches 56 each of which is formed with an arcuate cut-out different from the others to accommodate projectiles of different diameters or calibers. Each adapter is further formed at its opposite sides with mounting lugs 57. When the adapter is mounted in the lower member 29, the lugs 57 respectively fit into and are received by the recesses 50. The lugs 57 and recesses 50 are preferably square so that the adapter is mounted in the member 29 in such a manner that it is held against rotation. When the adapter 55 is mounted in the upper member 30, the square lugs 57 on the former fit into the recesses 52 of the latter and a pin 58 is passed through the aligned bores 53 in the jaw member 30 and through an aperture or bore 59 in the adapter 55. Since the lower adapter 54 is held in the lower jaw by its own weight, it is not necessary that a pin be provided to secure the two together. However, since the adapters 54 and 55 are interchangeable, each adapter is usually provided with an aperture 59.

In the use of the apparatus described for the disassembling of a cartridge, the transverse supporting members 14 will serve to carry a casing in the V-blocks 16 in the manner indicated in broken lines in the drawings. The V-blocks 16, by means of the bolts 17 and slots 18, may be adjusted vertically on the members 14 to accommodate casings of different calibers. Each of the adapter jaws 54 (55) will have been positioned in its supporting member 29 or 30. It will be noted that the square formation of the lugs 57 corresponds with the four different-sized notches 56 so that each adapter may be mounted in its supporting jaw in any one of four positions. The adapters are so mounted that the selected notches 56 are complementary and fit the particular projectile to be gripped. The threaded sleeve 47 and threaded member 46 are moved into locked position and tightened so that the adapter jaws 54 and 55 positively grip the projectile of the shell. The proper size adapter 21 is inserted into the semicircular recess in the case-gripping means 19-22 so that the rim of the case is snugly fitted therein. The handwheel 28 is turned to rotate the screw 24 so that the case-gripping means 19-22 is moved longitudinally on the base in a direction away from the projectile gripping means, which is locked to the base 10 by the detent means 31-37. When the shell case is separated from the projectile, the two parts (projectile and shell) remain supported in the apparatus, the case being held by the V-blocks 16 and the case-gripping means 19-22, and the projectile being held in place by the projectile-gripping means 29-30. The operating handle 48 may then

be turned to release the connection between the upper and lower gripping members 30 and 29 so that the projectile may be removed from the apparatus.

In order that the apparatus may accommodate a wide range of shells of different calibers for the disassembling operation, other adapters patterned after the one shown in Figs. 7 and 8 may be included as part of the accessories of the apparatus and such additional adapters may be formed with notches (similar to the notches 56) of various sizes. Other modifications and alterations may be made in the preferred form of invention herein illustrated and described, all of which will occur to those skilled in the art. It will be understood, of course, that these and other modifications and alterations may be made without departing from the spirit and scope of the invention as set forth in the appended claims.

I claim:

1. In an instrument for extracting the projectile of a cartridge from its casing, a frame comprising a pair of elongated channel members, means securing said members in horizontally-spaced, parallel, side-by-side relation with the flanges of each channel member extending toward, and disposed oppositely the corresponding flanges of the other member, cartridge supporting means mounted on and between the upper flanges of said channel members for longitudinal adjustment therewith, a lower semi-circular clamp element slidably adjustable on and along the upper flanges of said members, an upper semi-circular clamp element pivoted at one end to a corresponding end of said lower clamp element, means pivotally carried by said lower clamp element and operable to engage said upper clamp element to force the other ends of said elements together to thereby clamp between said elements the projectile of a cartridge supported on said supporting means, an adapter carried by each said clamp element and adjustable to accommodate projectiles of different calibers, there being a series of holes in longitudinally-spaced relation along each said member, spring-pressed plunger means carried by said lower clamp element, each plunger means being cooperable with a selected one of said holes to releasably fix said clamp elements in longitudinally adjusted position therewith, gripping means slidably mounted on and between said upper flanges and adapted to grip the flanged end of the shell of a cartridge resting upon said supporting means, and power multiplying means connected with said gripping means and operable to positively move the same longitudinally along said channel members.

2. In an instrument for extracting the projectile of a cartridge from its casing, a frame comprising a pair of elongated members rigidly connected in horizontally spaced parallel side-by-side relation, a pair of spaced cartridge supports slidably mounted on and between said members and adapted to independently support a cartridge therebetween, each said cartridge support comprising a vertically adjustable block having a V-notch in its upper surface, means to secure each block in vertically adjusted position, clamping means slidably mounted on and between said members and adapted to grip the projectile of a

cartridge supported by said members, means to releasably secure said clamping means to said members in longitudinally-adjusted position therewith, said clamping means comprising a lower generally semi-circular element slidable on said members, an upper generally semi-circular element pivoted at one end to an end of said lower element, means operable to draw the other ends of said elements together, said elements having their confronting faces recessed, a pair of adjustable adapters each having a plurality of arcuate notches in its periphery, each notch being adapted to accommodate a shell casing of a caliber different from the others, each adapter being constructed to fit a recess with a selected notch in projectile gripping position, interengaging means between each said adapter and its clamp element to hold said adapter in its selected position of rotatable adjustment, gripping means slidably mounted on and between said members for gripping the head of the casing of a cartridge resting on said supports, and power multiplying means carried by said members and engaging said gripping means for moving the same longitudinally along said members.

3. In a machine for separating the projectile of a cartridge from its casing, a pair of elongated beam members, means rigidly connecting said members in horizontally-spaced parallel relation, vertically-adjustable cartridge-supporting means mounted on and between said members for longitudinal adjustment therewith, clamping means longitudinally adjustable on and along said members to grip the projectile of a cartridge carried on said supporting means, means to releasably secure said clamp means in longitudinally-adjusted position, gripping means longitudinally adjustable on and along said members and adapted to grip the flanged head of the shell of a cartridge carried on said supporting means, said gripping means comprising a head having an undercut semi-circular channel therein, an adapter adapted to removably fit said channel, said adapter having a semi-circular groove to receive the flange of the head of a cartridge casing of predetermined diameter when supported by said supporting means and power-multiplying means carried by said members and operable to engage and positively move said gripping means on and along said members toward or away from said clamping means.

ARTHUR R. KINZLE.
